UNITED STATES PATENT OFFICE.

EDMUND OCUMPAUGH, 2d, OF ROCHESTER, NEW YORK.

PRINTING-MACHINE.

1,161,071.

Specification of Letters Patent. Patented Nov. 23, 1915.

Application filed January 23, 1914. Serial No. 813,873.

To all whom it may concern:

Be it known that I, EDMUND OCUMPAUGH, 2d, a citizen of the United States, and resident of Rochester, in the county of Monroe and State of New York, have invented certain new and useful Improvements in Printing-Machines, of which the following is a specification.

This invention relates to printing-machines of the type in which any of a series of characters or words may be impressed selectively upon a check or other article.

The invention, while having features applicable to various machines of this type, is particularly applicable to machines of the kind designated as "check-writing machines", in which characters are provided for filling in the amounts of bank-checks.

The object of the invention is to improve the manually-operable mechanism by which both the selective and the impressing operations of the printing-means are controlled, and particularly to produce an arrangement in which two easily performed movements of a single manually-operable member serve for the accomplishment of both of these functions.

To the foregoing end the invention comprises the use of a manually-operable member which is capable of both lateral and longitudinal movements in a single plane, one of these movements being utilized for the selective operation, and the other for the impressing operation.

The invention further comprises simple and effective means whereby the manually-operable member, during its longitudinal movement, is locked against accidental lateral movement.

Finally, the invention comprises a novel arrangement of mechanism for connecting the manually-operable member with a rotatable type-carrying member or wheel, and with a movable platen, whereby the selective and impressing movements of these printing-means are transmitted to them from the manually-operable member.

In the accompanying drawings:—Figure 1 is a plan-view of a check-writing machine embodying the present invention, with a part of the casing broken away to show the interior mechanism; Fig. 2 is a vertical section on the line 2—2 in Fig. 1; Fig. 3 is a horizontal section on the line 3—3 in Fig. 2; and Fig. 4 is a partial vertical section on the line 4—4 in Fig. 1.

In the illustrated embodiment of the invention the printing-means comprise a rotatable type-wheel 5, carrying types expressive of various numbers, and a platen 6 by which a check may be pressed into engagement with the type-wheel. The manually-operable member is in the form of a head 7, mounted upon a plunger 8 which slides within a sleeve 9 projecting from a carrier 10. The carrier is mounted to oscillate upon a vertical axis or shaft 11, this shaft being journaled, at its ends, in a casing 12 which incloses the mechanism of the machine.

The oscillatory movements of the parts just described are communicated to the type-wheel to produce the rotation of the wheel by which selection is made among the characters thereon to be impressed upon the check. For this purpose a segmental gear 13, fixed to the shaft 11, engages a pinion 14 integral with a gear 15 which is connected, in turn, through gears 16 and 17, with the type-wheel, as shown in Figs. 1 and 2. Accordingly, a swinging movement of the manually-operable member 7 from one extremity to another of its path of movement causes a complete rotation of the type-wheel, while the parts may be arrested at any intermediate point. To indicate the required position of the parts, a pointer 18 is fixed upon the sleeve 9, and co-operates with a graduated scale 19 at the top of the machine.

The machine is preferably arranged to impress characters upon a check both by a cutting action and by the application of ink. The cutting action may be produced in the usual manner by the use of serrations in the platen 6 and the type, while ink is supplied to the type by means of rollers 20, as shown in Fig. 2.

The impressing operation is produced by forcing the plunger 8 rearwardly through the sleeve 9. This plunger is normally held in its forward position, as in Fig. 2, by means of a spring 21 coiled within the carrier 10, but the plunger has a beveled surface 22 which engages a ball 23 resting on the top of a rod 24. This rod extends axially through the shaft 11, which is made hollow for this purpose, and when the plunger 8 is repressed the ball and the rod 24 are forced downwardly. The lower end of the rod engages an adjusting-screw 25, threaded into a lever 26 which is fulcrumed at 27 on the frame of the machine, and the lever carries the platen 6 at its forward end. A spring

28, engaging a projection 29 on the lever 26 as shown in Figs. 3 and 4, normally holds the parts in the position illustrated, in which the platen is sufficiently removed from the 5 type-wheel to permit a check to be placed upon the work-table 30 beneath the type-wheel. The position in which the check is so placed is determined by an adjustable gage 31 movable over the top of the table. 10 The check is held yieldingly upon the table by a spring-pressed roller 32, and after each impressing operation it is fed forward by means of serrated feed-rollers 33, working beneath the table and actuated automatically by any ordinary or suitable means. In swinging the head 7 from side to side to set the type-wheel it is necessary that it be brought to rest exactly in a position in which one end of the characters in the type-wheel will be in printing position. To assist this setting-operation a sliding detent 34 is mounted in the carrier 10 this detent having a conical end which co-operates with a series of depressions in the casing 12, and being 20 forced outwardly into engagement therewith by the spring 21. Since the detent 34 yields readily to movement of the manually-operable mechanism it permits the parts to be set with facility, while at the same time it tends to prevent them from coming to rest in any intermediate position. Since its action is not positive, however, I employ additional means for positively locking the manually-operable member against accidental 30 lateral or selective movement while the impressing movement is being performed. To this end a locking-pin 35 is fixed to the plunger 8, and projects downwardly through a slot in the sleeve 9. This pin operates with a series of holes 36 in the casing 12, these holes corresponding in position to the several selective positions of the mechanism. The pin is normally out of engagement with the holes, but upon a rearward 40 sliding movement of the plunger the first part of this movement causes a locking action by the pin, so that when the final and greatest pressure is imposed upon the plunger, to cause the platen to press the work 50 firmly against the type-wheel, there is no possibility of accidental movement of the parts from their position of correct registration.

To facilitate the impressing operation two finger-holds 37 are provided upon the sleeve 9, and the operator places the first and second fingers upon these finger-holds while pressing the thumb against the concave face of the head 7. With the hand in this position the manually-operable members may easily be swung from side to side and then repressed, thus performing successively, with convenience, the selective and impressing operations, and this arrangement also permits a considerable pressure to be im-

parted to the platen without severe effort on the part of the user.

My invention is not limited to the embodiment thereof hereinbefore described and illustrated in the accompanying drawings, but it may be embodied in various other forms within the nature of the invention as it is defined in the following claims.

I claim:

1. In a printing-machine, the combination, with printing-means adapted to impress any of a series of characters selectively, of mechanism for actuating the printing means to produce a selective operation and an impressing operation thereof, comprising a manually-operable member adapted to swing laterally, in a substantially horizontal plane, to cause one of said operations, and movable in the same plane, but transversely to its first said movement, to cause the other of said operations.

2. In a printing-machine, the combination, with printing-means adapted to impress any of a series of characters selectively, of mechanism, for actuating the printing-mechanism, comprising a manually-operable plunger movable laterally to cause a selective operation of the printing-means, and movable longitudinally to cause an impressing operation of the printing-means.

3. In a printing-machine, the combination, with printing-means adapted to impress any of a series of characters selectively, of mechanism, for actuating the printing-mechanism, comprising a manually-operable plunger movable laterally to cause a selective operation of the printing-means, and movable longitudinally to cause an impressing operation of the printing-means, and means for locking the plunger against lateral movement during its longitudinal movement.

4. In a printing-machine, the combination, with printing-means adapted to impress any of a series of characters selectively, of mechanism, for actuating the printing-means, comprising a manually-operable member movable in one direction to cause a selective operation of the printing-means, and in another direction to cause an impressing operation, yielding means tending to arrest the selective movement of the manually-operable member in one of a series of positions corresponding to the selective positions of the printing-means, and means for positively preventing further selective movement of the manually-operable member during its impressing movement.

5. In a printing machine, the combination, with a type-wheel and a platen, of a hollow shaft geared to the type-wheel so as to rotate it by rocking movement of the shaft, a manually-operable member, projecting laterally from, and connected with, the

shaft, by which the shaft may be rocked, a plunger slideable within the shaft, a second manually-operable member carried by the shaft and movable relatively thereto, said 5 second manually-operable member coöperating with the plunger to move it within the shaft, and connections between the platen and the plunger for actuating the former from the latter.
